(57) **CLAIM**

The ornamental design for a pooper scooper with cap, as shown and described.

DESCRIPTION

FIG. 1 is a front, right, top perspective view of the pooper scooper with cap, in an open state of use;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front view of the pooper scooper with cap in an open state of use and cap off;

FIG. 9 is a front view of the pooper scooper with cap in a closed state of use and cap off;

FIG. 10 is a front view of the pooper scooper with cap in a closed state of use; and,

FIG. 11 is a front view of the pooper scooper with cap in a closed state and cap on.

The broken lines in the drawings depict portions of the pooper scooper with cap that form no part of the claimed design.

1 Claim, 11 Drawing Sheets
